UNITED STATES PATENT OFFICE.

GEORGE E. P. COLLINS, OF SPRINGFIELD, MASSACHUSETTS, ASSIGNOR TO BIRNIE PAPER COMPANY, OF SPRINGFIELD, MASSACHUSETTS, A CORPORATION OF MASSACHUSETTS.

APPARATUS FOR LINING ENVELOPES.

Application filed July 21, 1926. Serial No. 124,917.

This invention relates to improvements in machines for patching blanks, that is in machines for affixing a strip or patch of paper in a certain relation on another sheet or blank. The invention in its present preferred form is directed particularly to improvements in machines or apparatus for lining envelopes.

In lining envelopes it is customary to secure to an unfolded envelope blank a liner or patch considerably smaller than the blank, which liners are of a decorative character so that when the envelope blank is folded to form an envelope they give to the envelope and especially the inner side of its flap the appearance of an interior lining.

To attain the most desirable appearance, the liner should be accurately positioned on the blank, but obviously where the blank and liner are secured together merely by the ordinary hand operation this is difficult and furthermore is a slow process.

One important feature of this invention is the provision of a machine in which stacks 25 of blanks and of patches or liners are disposed in definite relative positions and after a gluing operation a blank and a liner are brought into superposed relation for a joining or affixing operation and is accomplished 30 by transferring the uppermost blank of one stack onto the uppermost liner of the other stack.

Other features of the invention will be 35 apparent from the following description of the present preferred form thereof, although it will be understood that in practicing the invention it may be varied or modified within wide limits wherever it is desired to secure together separate elements in the form 40 of a patch and a blank, such as a liner and an envelope blank.

In the drawings:

Fig. 1 is a side elevational view of a machine embodying the features of the invention;

Fig. 2 is a plan view of the machine taken on the line 2-2 of Fig. 1 with certain parts omitted for clearness;

Fig. 3 is a sectional elevational view taken on the line 3-3 of Fig. 2;

Figs. 4, 5, 6 and 7 are diagrammatic views showing the various relative positions of certain important parts of the machine as they act upon the blank and liner;

Fig. 8 is a plan view of one of the lower

blank gripping devices which cooperate with the upper gripping devices to engage and reverse a blank and to transfer it from one stack to the other;

Fig. 9 is a side elevational view of the 60 same;

Fig. 10 is a sectional view on the line 10-10 of Fig. 9;

Fig. 11 is a plan view of an envelope blank and liner in superposed relation; and 65

Fig. 12 is a view of the envelope blank folded into the form of an envelope showing the liner as it appears on the flap.

Referring to the drawings in detail, 1 represents a table or bed plate for supporting the various mechanisms constituting the machine and is supported by side frames or standards 2 beneath and secured to opposite sides of the table. A main driving shaft 3 is rotatable in suitable bearings of the supporting frames 2 and may be driven by any suitable means such as by a pulley (not shown) which may readily be secured to either end thereof.

A plurality of envelope blanks E and liner blanks L, which will be termed "liners", are held in stacked piled relation by adjustable guides E¹ and L¹ as shown in Fig. 2. These guides are arranged for relative adjustment so as to accommodate different sizes of blanks and liners and to accurately position the stacks in desired relative positions. It will be understood that any reference to envelope blanks and liners is intended as a general term to include any sheet or other blank and to any patch or other sheet for securing to said blank.

A vertically movable rear guide 10, against which the stack of liners L abuts, is resiliently mounted on springs 11 so as to 95 be compressible as shown in Fig. 3, for the purpose as will later appear.

A hold down member 12 (see Fig. 2) in the form of a bail is pivoted to the frame at 13 and carries prongs or hold downs 14 which 100 rest on the uppermost blank of the stack so that only the uppermost blank may be removed or lifted from the stack by the mechanism now to be described.

A cross head 15 is fixed to the upper ends 105 of vertically reciprocable rods 16 which are guided at opposite sides of the bed and carries a blade or dauber 17 and spaced apart daubers 18 for daubing one end of the uppermost blank of the stack with a stripe of 110

glue *g* and for daubing the said blank at its other end with separated dots as at *g'*. The cross bar is arranged to raise and lower in a proper timed relation with the other parts 5 of the mechanism to thereby bring the daubers into engagement with the uppermost blank of the stack for applying the glue daubs as indicated.

As the daubers are brought onto the blank, there is naturally a tendency for the blank to adhere to the daubers and to be moved upwardly by the upwardly moving daubers. This is desirable in so far as the dauber 17 is concerned as it is desirable to raise the forward end of the blank for the purpose to be later described. To prevent the rear end of the blank being raised by the daubers 18, resiliently mounted strippers 19 are carried by the daubers 18 which are spring pressed downwardly and are adapted and arranged to yieldingly bear on the uppermost blank to hold said blank down and effect a stripping of the daubers 18 from the blank as they raise upwardly therefrom after a daubing operation. The daubers 17 and 18 receive their supply of adhesive material, which may be glue, gum or the like, in the following manner.

A reciprocable carriage 20 is guided in a pair of horizontal tracks 21 suitably supported and disposed above the bed plate at opposite sides of the stacks of blanks and has a transverse roll 22 rotatable therein which is arranged as the carriage is reciprocated back and forth to roll across or contact with the daubing surfaces of the daubers 17 and 18 and to supply adhesive thereto.

40 A reservoir 25 for containing adhesive material such as glue is carried by a U shaped upright 26 extending across and above the bed plate 1 and has a rotatable glue roll 27 and a scraping device 25' of usual form. This roll is preferably rotated by a belt (not shown) from the driving shaft of the machine, or it may be driven in any other suitable manner so as to rotate to present a film of glue to be taken up by the reciprocable roll 22 as it is moved into engagement therewith as shown in Fig. 3. A forwardly extending plate 27' of the glue reservoir 25 is provided with a slot to allow the dauber 17 to pass therethrough and functions, as the end of the dauber is moving upwardly therethrough and carrying the end of the blank, to strip the blank therefrom, after which the said end is engaged by gripping mechanism now to be described.

A transverse rotatable or oscillatable shaft 28 is carried by the carriage 20 and has one or more gripping fingers 29 fixed thereto and arranged to cooperate with a transverse plate 30 to form an "upper" blank engaging device for engaging or holding the end of a blank as it is raised upwardly by and stripped from the dauber 17. The shaft is

preferably urged clockwise by a coil spring (not shown) and which may be attached thereto in any of the well known manners so that in effect the end of the blank is gripped by the grippers due to the action of said spring. Other means, later to be described, operate to move the shaft counter-clockwise against the action of the spring at a proper time to release a blank and to allow it to rotate clockwise so that a blank is engaged by the grippers. 75

Gripper bars 35, disposed below the tracks 21 and at either side of the stacks of blanks, are reciprocable in guides 36 supported by the table and are rigidly connected at their forward ends by a transverse brace or bar 37. "Lower" grippers G are fixed to the rear end of each of the bars 35 for engaging the rear end of the blank after its forward end is engaged by the "upper" gripper just referred to. Said "lower" grippers G each comprises a member 40 pivoted at 41 to a gripper frame 43, the member 40 having oppositely disposed fingers 42. The member 40 is adapted to swing so that either finger 42 will move towards and away from the face of the frame for clamping a blank between said fingers and said frame. A rod 42' loosely slideable in the frame and pivoted to the member 40 has a compression spring 43' therearound which acts upon the member 40 so as to hold it in either the position shown by dotted or full lines.

As the grippers are moved to the left or towards the rear of the machine, they are in an open position, as in full lines in Fig. 10. Gripper actuating members 44, as shown in Figs. 1 and 3, have depending portions 44' arranged to lie in the path of the fingers 42 of the grippers and against which the fingers will abut so as to close the finger against an envelope blank for pinching and holding said blank between said finger and the gripper frame. Other devices 45 in the form of upstanding rods are also disposed in the path of said grippers at the forward end of the bed plate to move them in a reverse direction or to open the grippers and release a blank held thereby as will later appear.

A presser member 50 comprising a plate, 115 preferably having a resilient face such as 51, is carried by a reciprocable rod 52 which is guided in a bearing 53 of the cross bar 26. This presser is arranged to press the blank onto the liner as will later appear and is 120 also adapted to press the liner onto the stop plate 10 and to depress the stop plate as it bears upon the blank and liner.

A driving feed roll 60 has its opposite end 125 trunnions in suitable bearings 61 and is driven from the main shaft 3 by means of the belt 62 and pulleys 63, as shown in Fig. 1. A lower feed roll 66 cooperating with the roll 60 has its trunnions rotatable in uprights 67 which are adjustable in 130

spaced arms 68' of a vertically reciprocable roll supporting member 68. The member 68 is fixed to a reciprocable rod 69 which is guided on its upper end in a bearing 70 secured to the bed plate. The rod 69 is guided for a reciprocating movement at its lower end by a fork 71 of usual construction which is slideable on the main shaft 3. A cam (not shown) and which may be of ordinary form, is fixed on said shaft 3 and in conjunction with a suitable cam roll carried by the fork is arranged to raise and lower the rod and consequently the roll 68 so that the end of the blank may be engaged between the rolls when delivered thereto by the grippers. The mechanism for operating the other parts of the machine in a proper timed relation will now be described.

The grippers and bars 35 are reciprocated by a lever 75 which is oscillatable on a shaft 76 carried by the side frames 2. The lever has an arm 77 for carrying a cam roll 78 in operable engagement with the face of an operating cam 79 of the shaft 3. A spring 80 is connected between the arm 77 and side frame 2 to properly hold the roll on the face of the cam and as the shaft is rotated the lever is rocked back and forth by the cam to move the gripper bars 35 and grippers G back and forth along the tracks.

The upper carriage 20 carrying the glue daubing roll is reciprocated along its tracks by swinging levers 82 at either side of the carriage. These levers are fixed to opposite ends of an oscillatable shaft 83 and at their upper ends loosely embrace suitable pins 82' at the sides of the carriage. An arm 84 of one of levers 82 is pivotally connected to a rod 85 which is provided with a fork 86 slideable on the shaft 3. A cam of usual form (not shown) is fixed on said shaft and in conjunction with a suitable roll on said fork functions to raise and lower the rod to swing the levers 82 back and forth and thereby reciprocate the carriage.

A stop 90 (see Fig. 1) carried by the upright 21' is disposed in the path of an arm 91 of a lever 92 on the end of the gripper shaft 28 and as the carriage is moved forwardly or to the left the arm 91 of the lever 92 will abut the stop 90 so as to rotate the shaft and grippers 29 counterclockwise against the action of the spring connected to the shaft. This movement of the grippers will release an envelope blank held between the grippers and plate 30. As the carriage returns to the right, the arm 91 is released by the stop so that the grippers actuated by the spring will close against the plate; but in order to hold the grippers open to receive the end of a blank delivered thereto by the dauber, a member 115 is provided on the rod 16 which is arranged to lie in the path of an arm 116 of the lever 92. As the dauber is elevated to a point where the

blank will be stripped therefrom, the member 115 will release the lever 92 and allow said lever and shaft 28 to be moved clockwise by the spring and the grippers will close on the end of a blank carried upwardly by the dauber. Obviously, any other form of gripping devices may be employed, such as are used on wrapping machines or the like, the form shown being intended to illustrate a type that will function for the purposes described.

One of the cross head rods 16, which are guided in the bearings 100, has a shoe 101 on the lower end thereof resting on a cam roll 101' carried by the end of a lever 102 which is arranged for a rocking motion on shaft 76 while a suitable cam 102' on the main shaft acts upon the underside of said lever to raise and lower it, which movement in turn actuates the rods and daubers carried thereby.

A rod 110, reciprocable in the bed and having a fork 111 slideable on shaft 3 is actuated by a cam on the main shaft 3, has a member 113 on its upper end for carrying the upper end of the reciprocable plunger rod 52 and is adapted to move the presser plunger 50 towards and away from the stack of liners.

It will be obvious that the operating mechanism described may be varied within wide limits as to form or that equivalent mechanism may be substituted therefor for operating the various parts in a proper timed relation.

The operation of the apparatus will now be described. Assume that the driving shaft is being driven from a suitable source of power and that the operation of the parts has been properly timed, and also that a stack of envelope blanks 3 and liners L therefor are in proper relative position and held therein by their respective guides.

The carriage 20 is reciprocated to the rear or to the left so that the daubing roll 22 engages the daubers 17 and 18 to supply them with glue. When the carriage has returned again to the position at the right, or as shown in Fig. 2, the daubers 17 and 18 are lowered into contact with the uppermost envelope blank of the stack to apply the daubs of glue g and g' thereto. As the daubers ascend, the forward end of the uppermost blank is carried by the dauber 17 upwardly against the stripper plate 27 while the rear end of the blank is stripped from the daubers 18 by the strippers 19. When the blank contacts with the stripper plate, the upwardly moving rods carrying the member 115 will release the arm 116 of the arm 92 so that the shaft 28 will rotate clockwise to permit the clamps 29 thereof to clamp the end of the blank against the plate 30, as shown in Fig. 4. With the rear end of the blank resting on the stack and the forward

end being gripped as described, the blank will assume the oblique position shown in Fig. 4. With the blank in this position, the lower grippers G are moved to the left and their clamps closed by the members 44 so that the grippers will bite or clamp the blank on its opposite sides adjacent its rear end.

With the blank thus engaged or held at its opposite ends by the two sets of grippers, the upper carriage is moved to the rear or left while the lower grippers are moved forwardly or to the right. This movement effects a reversal of the blank, that is it is completely turned over so that the glue spots *g* and *g'* are now on the under side of the blank instead of on the upper side.

As the carriage approaches the end of its movement to the left, the member 90 acts upon the lever 92 so that the upper grippers 29 will release the end of the blank while the lower grippers still holding the blank continue in their movement to the right so as to transfer the blank to a position over the liners L. During the latter part of this movement to the right, the roll 68 is moved downwardly to allow the grippers G to carry the end of the blank between the rolls 60 and 66.

The gripper operating members 45 are located so as to open the grippers and release the blank as the blank is properly positioned over the stack of liners. When the blank is released and resting on the liners, the presser 50 descends and presses upon the blank and upon that portion of the blank resting upon the plate 10, thus biting the blank between it and the upper end of the plate to prevent a shifting movement and at the same time causing the blank and liner to adhere together.

As the presser member is elevated after the pressing operation, the lower roll 66 is elevated and in ascending it engages the lower face of the blank and raises the blank upwardly. When the roll 66 engages the rotating roll 60 it is rotated thereby and cooperates therewith to press the blank and liner together and to feed them forwardly onto a table T at the forward end of the table. The lined blanks delivered to the table T may be formed into envelopes (shown in Fig. 12) by any of the usual folding or forming machinery.

From the foregoing, it will be observed that I have provided a machine for assembling an envelope blank and liner in which the uppermost blank of a stack is glued and then transferred by a reversing movement onto the uppermost liner of a stack and pressed thereagainst.

I am aware that many changes may be made in the form of the invention without departing from the scope thereof and I prefer therefore to be limited by the following

claims rather than by the foregoing description.

What I claim is:

1. A machine of the class described comprising in combination, means for holding a supply of envelope blanks and liners in separate stacks, a daubing and blank gripping device for engaging with the uppermost blank of one stack, and independently movable devices for engaging opposite ends of said blank for transporting said blank over the other stack, the said devices being arranged to reverse said blank during its movement from one stack to the other. 75

2. A machine of the class described comprising in combination, means for holding a supply of blanks and liners in separate stacks, and devices for engaging opposite ends of the uppermost blank of one stack operable in opposite directions to reverse said blank and deposit it on the uppermost blank of the other stack. 80

3. A machine of the class described comprising in combination, means for holding a supply of blanks and liners in separate stacks, devices for engaging opposite ends of the uppermost blank of one stack operable in opposite directions to reverse said blank and deposit it on the uppermost blank of the other stack, and a gumming device for gumming the uppermost blank of one stack and for inserting an end of said blank in one of said devices. 90

4. A machine of the class described comprising in combination means for holding a supply of blanks and liners in separate stacks, devices for engaging opposite ends of the uppermost blank of one stack operable in opposite directions to reverse said blank and deposit it on the uppermost blank of the other stack, a gumming device for gumming the uppermost blank of one stack and for inserting an end of said blank in one of said devices, and a presser member for pressing said reversed blank onto said stack. 100

5. A machine of the class described comprising in combination means for holding a supply of blanks and liners in separate stacks, devices for engaging opposite ends of the uppermost blank of one stack operable in opposite directions to reverse said blank and deposit it on the uppermost blank of the other stack, a gumming device for gumming the uppermost blank of one stack and for inserting an end of said blank in one of said devices, and a presser member for pressing said reversed blank onto said stack, and rolls for removing said uppermost blank from said stack. 110

6. A machine of the class described comprising in combination, means for holding envelope blanks and liner blanks in stacked relation, a dauber for applying adhesive to the uppermost blank of one stack and for elevating said blank above said stack, 125

- and grippers for engaging opposite ends of said blank being movable independently in opposite directions to reverse said blank and superpose said blank on the other stack.
- 5 7. A machine of the class described comprising in combination, means for holding envelop blanks and liner blanks in stacked relation, a dauber for applying adhesive to the upper blank of one stack and for elevating said blank above said stack, grippers for engaging opposite ends of an elevated blank, the said grippers being independently movable in opposite directions to reverse said blank, means for releasing one of said 10 grippers whereby the other gripper may superpose said reversed blank on the uppermost blank of the other stack, and means for pressing said superposed blanks together and for removing the same from the stack.
- 15 8. A machine of the class described comprising in combination, means for holding a supply of envelope blanks and liners in separate stacks, means for elevating an end of the uppermost blank of one of said stacks, grippers for engaging opposite ends of said blanks operable in opposite directions to reverse said blank and to superpose the same on the uppermost blank of the other stack, and means for disengaging said grippers 20 from said blank and cooperating rolls for engaging said superposed blanks to remove them from said stack.
- 25 9. A machine of the class described comprising in combination, means for holding a supply of envelope blanks and liners in separate stacks, a vertically reciprocable dauber for engaging with the uppermost sheet of one of said stacks adapted to elevate an end of said blank, a horizontally re-
- ciprocal carriage movable back and forth above said stack, a gumming device carried by said carriage adapted to engage with and supply said dauber with adhesive material, and separate gripping devices for engaging the opposite ends of said blank, the said 45 grippers being arranged and adapted to move in opposite directions to reverse said blank and deposit the same on the uppermost blank of the other stack.
10. A machine of the class described comprising in combination, means for holding a supply of envelope blanks and liners in separate stacks, a vertically reciprocable dauber for engaging the uppermost blank of one stack and applying adhesive thereto 50 adapted to raise an end of said blank above said stack, a movable carrier above said stack, a daubing device carried by said carrier adapted to supply said dauber with adhesive, a gripper carried by said carrier for 55 engaging the elevated end of said blank, a movable gripper for engaging the opposite end of said blank, a pair of relatively movable rolls adapted to receive a superposed blank and liner, the said carriage and grippers adapted and arranged to simultaneously move in opposite directions to reverse said blank and superpose the same on the uppermost blank of the other stack in such a 60 position that an end thereof is disposed between said rolls, a vertically reciprocable presser disposed above said last-named stack for pressing said blanks together, and means for actuating said rolls whereby the superposed blanks are removed from said stack. 65 70 75

In testimony whereof I have affixed my signature.

GEORGE E. P. COLLINS.
